AIR GUN

Walter A. Tratsch, Chicago, Ill., assignor to Clarence E. Threedy, Chicago, Ill., as trustee

Application January 25, 1945, Serial No. 574,484

2 Claims. (Cl. 74-2)

1

This invention relates to new and useful improvements in air guns. More specifically the invention relates to a novel trigger mechanism for controlling the passage of air to the barrel of the gun to expel the shot therefrom.

The invention has for its principal object the provision of an improved construction of this character which will be highly efficient in use and economical in manufacture.

As a further and equally important object of the invention is the provision of mechanism having maximum speed of operation whereby to produce the maximum propulsion speed to the shot from the barrel.

More specifically in this connection, the invention has for an object the provision for opening an air valve to the barrel of the gun by means of hammer action upon a plunger, thereby producing the maximum speed of expulsion of the shot from the barrel of the gun.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of the trigger mechanism embodied in the invention;

Fig. 2 is a perspective view similar to Fig. 1 showing the parts in cocked position ready for impingement upon the valve plunger embodied in the invention;

Fig. 3 is a vertical sectional detail view of certain parts of the trigger mechanism, showing the hammer in impinged engagement with the valve plunger embodied in the invention;

Fig. 4 is a vertical sectional detail view of a proposed valve mechanism embodied in the invention;

Fig. 5 is a perspective view of the trigger mechanism embodied in the invention showing a modified form of construction;

Fig. 6 is a perspective view similar to Fig. 5 but showing the parts of the trigger mechanism in a different position with respect to each other.

The present invention constitutes an improvement over that shown in my companion application filed on December 26, 1944, Serial No. 569,768, now abandoned, and like the invention disclosed in that application the present invention constitutes an improvement over that shown in my Letters Patent No. 2,304,320, dated December 8, 1942.

The drawings of this present application illus-

trate the preferred form of construction by which the several objects of the invention are accomplished. In these drawings and as will be apparent from the description hereinafter to follow, the form of the various parts does not enter into the invention, and the form shown in the drawings is to be considered merely the preferred form of construction for purposes of illustration of this invention.

10 In this respect, referring to Figs. 1 to 4 inclusive, the present invention includes a mounting plate 10 which is associated, in a suitable manner, with the breech block of the gun. On this mounting plate 10, at one end thereof, is mounted a valve housing 11. This valve housing 11 is in the form of a block 11 and provides a port 12 which has communication with a shot tube 13. This port 12 communicates with a tube 15 mounted in a counterbore 16 formed in the block 11. A port 18 communicates with the port 12. A valve seat is indicated at 19, and this valve seat closes an orifice 20 which communicates with a duct 21 in turn having communication with a suitable compressed air line 22. The valve tube 15 includes a packing nipple 23 which is threaded upon a thread-bearing boss 24, and mounted for slideable movement in the valve tube and comprising a valve head 25, is a plunger or plunger rod 26.

20 Communicating with the port 12 is a shot delivery duct 27, in turn communicating with a shot tube 28 by means of which the shots are confined in a manner disclosed in my Patent No. 2,304,320, it being pointed out that the manner of supplying the shots to the supply tube 28 does not constitute a part of this present invention.

25 As a shot 29 is delivered to the duct 27, it will be disposed in the path of a plunger rod 30 carried by a piston 31 slidably mounted in a tube 32 having a bifurcation 33 formed in one side thereof for the passage of the piston-operating arm 34, said arm being referred to more in detail hereinafter.

30 The plunger 26 has its outer end portion 35 slidably journaled through a lug 36 formed as an integral part of the mounting plate 10. On this plunger 26 is a fixed plunger head 37 and disposed between this plunger head 37 and the lug 36 is an expansion spring 38 which normally forces the plunger 26 in a left-hand direction as viewed in Fig. 1.

35 The mounting plate 10 carries a pintle 39, and pivotally supported by this pintle 39 is the lower end portion 40 of a hammer 41, the hammer 41

having a bifurcation 42 formed in its upper end for the reception of the plunger 26.

The hammer 41 is normally held against the plunger head 37 by means of a spring 43, one end of which is connected as at 44 to the lug 36, and the other end 45 being connected to the hammer 41. This hammer 41 has a shank 46 which provides a plate 47, having a slot 48 formed therein through which projects a latch arm 49 having a latch head 50. This latch head 50 is adapted to engage the adjacent wall portion 51 of the plate 47 of the shank 46. This latch arm is pivotally connected as at 52 to a trigger head 53, pivotally connected to the mounting block 10 by means of a pintle 54. The latch arm 49 is normally held in engagement with the plate portion 47 of the shank 46 by means of a spring 55, one end of which is connected as at 56 to the latch arm and the opposite end portion of spring 55 to a transverse wall 57 of the trigger 58, the said trigger providing a finger piece 59.

Pivottally connected by means of a pintle 60 to the mounting plate 10 is the arm 61 which operates the piston 31. This arm 61 has an elongated slot 62 formed therein, and operating in this slot is a pin 63. The arrangement is such that when the trigger 58 is pulled backward against the action of the spring 64 by application of the finger of the operator upon the finger piece 59, the pin 63, riding in the slot 62, will bear against the top edge of the slot 62 of the arm 61 and elevate the arm 61 to the position shown in Fig. 2, and in turn elevate the plunger 30 in the duct 27 to position the shot 29 in the port 12. Simultaneously with this action, the latch arm 49, being caused to move forward, will engage the edge 51 of the bight portion 48 and pivot the hammer 41 away from the plunger head 37 against the action of the spring 43. This will dispose the curved tail 65 of the latch arm 49 in contact with a pin 66 carried by the mounting plate 10, so that upon further movement of the latch arm 49 by the action of the trigger 58, the curved portion 65 of the latch arm 49 will be caused to cam against the pin 66. This camming of the curved portion 65 of the latch arm 49 against the pin 66, will pivot the latch arm so as to disengage the latch head 50 from the wall 51 of the bight portion 48 of the hammer 41, whereupon, under action of the spring 43 (which in the meantime has been expanded by this movement of the mechanism), the hammer 41 will be caused to pivot in an opposite direction, striking the plunger head 37 with an impact force sufficient to quickly move the plunger 26 against the action of the spring 38. This microscopic movement of the plunger 26 will open the passage through the port 18 to admit the compressed air into the port 12 to eject the shot therefrom with microscopic action.

I have found from actual practice and experience that the best result and greatest speed of an air rifle shot is best obtained by the quickness in the operation of opening and closing the valve. This is accomplished by a trigger mechanism constructed in accordance with the foregoing description.

In Figs. 5 and 6 I have illustrated a slightly modified form of construction of the invention. In this form of construction the plunger 26 is journaled between the angled end portions 67 and 67' of a bracket 69 secured in any suitable manner to the plate 10. The plunger 26 has an enlarged head portion 70 formed at its outer end portion. Pivottally carried by a pintle 71 in turn carried by the mounting plate 10 is an arm 72

which is adapted to bear against the head 70, as shown in Fig. 6. This arm 72 pivotally carries at its outer end, as at 73, a trip plate 74. Mounted between an enlarged portion 73' of the plunger 26 and the angled portion 67 of the plate 69, is an expansion spring 74'.

The trigger 75 is pivotally connected as at 76 to the mounting plate 10 and includes a projection 77 which is adapted to engage a wall of the valve housing 11, to limit its pivotal movement in a clockwise direction. To the finger portion 78 of this trigger 75 is pivoted, as at 79, a latch arm 80 providing a latch head 81. This latch head 81 is adapted to have engagement with a lug 82 of an arm 83 pivotally mounted to the mounting plate 10 as at 84. The arm 83 is normally urged to pivot in a clockwise direction by means of a spring 85 having its medial portion wound as at 86 upon the pivot pintle 84 and having one end portion 87 engaging the arm and an opposite end portion 88 engaging a pin 89 carried by the mounting plate 10. The arm 83 has an extension 90 provided with a lateral cylindrical projection 91 at its extremity. A stop pin 92 is carried by the plate 10 and is adapted to limit the pivotal movement of the arm 83 by action of the spring 85.

The arrangement is such that when the trigger 75 is pivoted in an anticlockwise direction, the latch head 81, being in engagement with the lug 82, will pivot the arm 83 in a clockwise direction about its pivot 84 against the action of the spring 85 until the cam end portion 93 of the latch arm 80 cams over pin 94 carried by the mounting plate 10. This camming of the latch arm 80 over pin 94, releases the latch arm from engagement with the lug 82 whereupon the arm 83 is pivoted in an anticlockwise direction in snap action under the action of the spring 85. In this pivotal movement of the arm 83 the pin 91 will strike against the edge 95 of the trip plate 74. Since this trip plate is limited by the angled end portion 96 which engages the edge 97 of the arm 72 as the pin 91 strikes against the edge 95 of the trip plate 74, the arm 72 will be caused to pivot in a clockwise direction in snap action, and this action of the arm 72 is transmitted to the plunger 26 which moves with great speed to open the valve port 18 for reasons hereinbefore set forth.

In its movement in a clockwise direction about the pivot 84, the arm 83 will engage the trip plate 74 and, inasmuch as this plate 74 is free to pivot in an anticlockwise direction, the arm 83 will, in pivoting in the direction stated, be free to move to the right of the trip plate 74, as viewed in Fig. 6.

In the form of construction shown in Figs. 5 and 6, I have not illustrated nor described the means of delivering the shot to the structure 11, as such means does not constitute a part of the present invention and any means for that purpose may be employed, such for example that shown in my Patent No. 2,304,320.

By the employment of the mechanism shown in the modified form of construction, a trigger mechanism is provided which is positive in its operation and which, like, the preferred form of construction, will result in rapid expulsion of the shot from the shot tube within the barrel.

While I have illustrated and described the preferred form of construction for carrying my invention into effect, this is capable of variation and modification without departing from the spirit of the invention. I, therefore, do not wish to be limited to the precise details of construction

set forth, but desire to avail myself of such variations and modifications as come within the scope of the appended claims.

Having thus described my invention, what I claim as new and desire to protect by Letters Patent is:

1. An air gun comprising a mounting structure, a valve structure on the mounting structure including a plunger having an enlarged portion, means supporting said plunger from said mounting structure for movement in opposite directions with respect to its length, spring means for moving said plunger in one direction, trigger means for moving said plunger against the action of said spring means comprising an arm pivotally carried by the mounting structure, means for pivoting said arm in hammer-like action against said enlarged portion to move the plunger against the action of said spring means, means adapted to have latched engagement with said arm for pivoting said arm in an opposite direction, and means for disengaging said last mentioned means from engagement with said arm to permit said arm to be moved by said arm moving means in said hammer-like action against said enlarged portion.

2. An air gun comprising a mounting structure, a valve structure on the mounting structure including a plunger having an enlarged portion, means supporting said plunger from

5 means for moving said plunger in one direction, trigger means for moving said plunger against the action of said spring means comprising an arm pivotally carried by the mounting structure, means for pivoting said arm in hammer-like action against said enlarged portion to move the plunger against the action of said spring means, means adapted to have latched engagement with said arm for pivoting said arm in an opposite direction, and means for disengaging said last mentioned means from engagement with said arm to permit said arm to be moved by said arm moving means in said hammer-like action against said enlarged portion, said latch-disengaging means comprising a member carried by said mounting structure and adapted for camming engagement with an end portion of said latch means.

10 20 15 25 30

said mounting structure for movement in opposite directions with respect to its length, spring means for moving said plunger in one direction, trigger means for moving said plunger against the action of said spring means comprising an arm pivotally carried by the mounting structure, means for pivoting said arm in hammer-like action against said enlarged portion to move the plunger against the action of said spring means, means adapted to have latched engagement with said arm for pivoting said arm in an opposite direction, and means for disengaging said last mentioned means from engagement with said arm to permit said arm to be moved by said arm moving means in said hammer-like action against said enlarged portion, said latch-disengaging means comprising a member carried by said mounting structure and adapted for camming engagement with an end portion of said latch means.

WALTER A. TRATSCH.
